UNITED STATES PATENT OFFICE.

JOSEPH ATWOOD WHITE, OF PHILADELPHIA, PENNSYLVANIA, ASSIGNOR TO THE
MOORE AND WHITE COMPANY, OF PHILADELPHIA, PENNSYLVANIA, A COR-
PORATION OF PENNSYLVANIA.

PRESS-ROLL FOR PAPER-MAKING MACHINES.

1,222,501.

Specification of Letters Patent. Patented Apr. 10, 1917.

Application filed December 1, 1916. Serial No. 134,307.

To all whom it may concern:

Be it known that I, JOSEPH A. WHITE, a citizen of the United States, residing in Philadelphia, Pennsylvania, have invented 5 certain Improvements in Press-Rolls for Paper-Making Machines, of which the following is a specification.

One object of my invention is to improve the construction of press rolls, particularly 10 those used in paper machines, so that the roll will not deflect at the center under pressure.

A further object of the invention is to construct the roll so that it will be supported on its shaft some distance from each end in 15 order to keep the face of the roll in an absolutely straight line so that the pressure will be the same from one end of the roll to the other.

A still further object of the invention is to 20 provide for a slight movement where the shaft supports the shell.

In the accompanying drawings:

Figure 1 is a longitudinal sectional view 25 of my improved press roll;

Fig. 2 is an enlarged longitudinal sectional view of one end of the roll;

Fig. 3 is a sectional view on the line 3—3, Fig. 2; and

Fig. 4 is a sectional view showing means 30 for lubricating the bearings.

Referring to the drawings, 1 is the shaft on which the shell 2 of the press roll is mounted. This shaft has trunnions 3 at each end. The shaft, in the present instance, is 35 greater in diameter at the center than at the trunnions and has a tapered section 5 at each end connecting with a section 6 of even diameter. Keyed to each of these sections 6 is a ring 7 which must turn with the shaft. 40 The periphery of each of these rings 7 is slightly rounded, as clearly shown in the drawings, and the shell has a comparatively neat fit at this point on the rings. Fitting within each end of the shell is a ring 8, 45 which is keyed to the shell and connecting this ring and the ring 7 is a flexible coupling in the form of a shell 9, which encircles the shaft and fits snugly on the portion 6 of the shaft and within the ring 8 secured to the shell. Any suitable fastenings are provided 50 so that the flexible couplings will turn with the shaft and with the ring 7 and will turn the shell 2.

4, 4 are caps which are secured to the shaft

at each end and bear against the ends of 55 the shell so as to prevent independent longitudinal movement of the parts. The caps also prevent dust and dirt from entering the space between the roll and the shaft. The roll consists of two sections, in the present 60 instance, a cast body portion 10 and a face section 11 of rubber or metal, which is turned true. The usual practice is to run two of these rolls together under heavy pressure on the trunnions, and it will be noticed 65 that the shaft 1 supports the roll at a distance from each end so that the shaft may deflect considerably without affecting the face of the roll, the object being to keep the face of the roll in an absolutely straight line 70 so that the pressure will be the same from one end of the roll to the other.

It will be noticed that the shell has a comparatively loose fit on the ring 7 mounted on the shaft and is driven through the long 75 coupling sleeves 9 so that the shaft may be considerably deflected without affecting the face of the roll, but this driving connection is substantial and will resist the strains to which the roll is subjected.

In order to lubricate the bearings properly between the ring 7 and the shell, I may locate a series of graphite plugs 12 in the rings, as shown in Fig. 4.

I claim:

1. The combination in a press roll, of a shaft; a shell mounted thereon and forming the body of the roll, said shell bearing upon the shaft some distance from each end; and couplings connecting the shell with the 90 shaft.

2. The combination in a press roll, of a shaft having bearing portions some distance from its ends; a shell loosely mounted on the bearing portions; and couplings at each 95 end of the roll connecting the shell with the shaft.

3. The combination in a press roll, of a hollow shell; a shaft extending through the shell and projecting at each end and having 100 trunnions at the ends, said shaft being greater in diameter at the center than at the ends, the shell having bearings on the shaft some distance from the ends; and coupling sleeves connecting the shaft with the shell. 105

4. The combination in a press roll, of a hollow shell forming the body of the roll; a shaft extending through the shell and hav-

ing a trunnion at each end; two rings secured to the shaft, each ring being located some distance from the end of the roll; a ring secured to the shell near each end; and 5 a tubular coupling connecting the two rings so that the shell is driven through the couplings from the shaft.

5. The combination in a press roll, of a tubular shell; a shaft considerably less in 10 diameter than the interior of the shell and

having two rings secured thereto some distance from the end of the shell, the periphery of each ring being rounded and the bearing portion of the shell being flat; tubular couplings connecting the shell near its 15 outer end with the rings on the shaft so that the shell will turn with the shaft, but will have a slight movement thereon.

JOSEPH ATWOOD WHITE.
